UNITED STATES PATENT OFFICE.

CALVIN R. WAID, OF BIRMINGHAM, ALABAMA.

ROCKING GRATE-BAR.

1,151,746.

Specification of Letters Patent. Patented Aug. 31, 1915.

Application filed May 25, 1914. Serial No. 840,851.

To all whom it may concern:

Be it known that I, CALVIN R. WAID, a citizen of the United States of America, residing at Birmingham, in the county of Jefferson and State of Alabama, have invented 5 certain new and useful Improvements in Rocking Grate-Bars, of which the following is a specification.

My invention relates to an improvement 10 in rocking grate bars composed of a plurality of segments which are suitably connected together and provided at each end with trunnions upon which the grate bar rocks.

15 The object of my invention is to design a grate bar which is light but very strong for its weight, which can be cheaply cast, which is well ventilated, and which comprises the minimum number of different parts.

20 One feature of my invention relates to avoiding the casting of the trunnions integral with one or more of the grate bar segments and this I accomplish by mounting the segments on a section of pipe or tubing 25 on the ends of which I screw sleeves which hold the segments between them on the bar and serve as its trunnions.

Another feature of my invention relates 30 to the manner in which the several segments are interlocked and alined on the tubing.

Another feature of my invention relates 35 to the novel construction of the segments, one-half of which is offset relatively to the other so that the assembled segments produce a grate bar having the sections of the 40 segments on opposite sides of a vertical axial plane relatively staggered. The particular design of the segments is of importance for providing an effective ventilation 45 for the bar and for preventing it becoming clogged with cinders under normal operating conditions. With my construction of segment I dispense with the requirement for right and left hand castings and only two 50 patterns are required, one for the segment having the rocker arm and the other for the standard segment without the rocker arm.

My invention further comprises the novel 55 details of construction and arrangement of parts, which in their preferred embodiment only are hereinafter more particularly described, reference being had to the accompanying drawings which form a part of this specification, and in which:—

Figure 1 is a side elevation of my improved grate bar. Fig. 2 is a plan view of

Fig. 1. Fig. 3 is a side elevation of the segment carrying the rocker arm; and Fig. 4 is a similar view of the standard form of segment without the rocker arm.

60

Similar reference numerals refer to similar parts throughout the drawings.

In the embodiment of my invention illustrated in the drawings, the several grate bar segments are mounted on a section of pipe 65 or tubing 1, the outer ends of which are threaded and adapted to receive the sleeves 2 and 3 which serve as trunnions for the grate bar. The standard form of grate bar segment illustrated in Fig. 4 comprises a 70 hub 4 provided with a central opening 5 to receive the pipe 1 and having on one end face one or more V-shaped lugs 6 and on its other end face one or more V-shaped notches 7. Two lugs and two notches are 75 preferably used and they are oppositely disposed so as to interfit on adjacent segments. Each segment comprises two integral, relatively staggered fire heads 8 and 8^a which are joined at their centers to and supported 80 by a web 9 which is triangular in side elevation and merges into the hub 4 having a ventilating opening 10 extending axially therethrough. As seen in end elevation, Fig. 1, this web 9 comprises reversely inclined 85 oppositely disposed faces 11 and 12 which extend from the inner ends of the fire heads 8 and 8^a and are tapered, as seen in Fig. 1, so that they merge into the relatively narrow base of the web 9. The left hand leg 90 of the web 9, as seen in Fig. 4, tapers downwardly and is inclined to the rear to bring its base near the rear end wall of the hub, while the right hand leg of the web is similarly tapered but is inclined to the front to 95 bring its base close to the front edge of the hub. By this arrangement the downwardly tapering legs forming the web 9 are inclined from each end and from each side of the segment toward the center of its fire 100 head, thereby giving me the strongest possible brace for the fire heads against strain from all directions and at the same time I succeed in eliminating as far as possible all unnecessary metal which would interfere 105 with ventilating the segment, it being noted that the arrangement of the webs permits the air to flow freely from the sides over the hubs and axially of the grate bar on both sides of the legs of the web 9.

110

The fire heads at their outer ends are supported by webs 13 and 14 which, as seen

in Fig. 1, are of less width than the top width of the fire heads, which in cross section taper downwardly and these fire heads also taper from their centers toward their ends. 5 As seen in Fig. 4, the fire heads are curved overhead to form a continuous arcuate fire supporting surface so that they will move under the fire with less disturbance than where the top surface is level. Wide ventilating openings 15 are provided between the web 9 and the webs 13 and 14 and the ventilating openings 10 and 15, being in alinement throughout the segments on the bar and being in communication with the side opening spaces provided between the webs 9, 13 and 14 of adjacent segments due to the inward taper of the webs, ample ventilating spaces are provided to prevent the excessive radiation of heat to the hubs or 20 the tubular support 1. The construction of the other type of segment used, which is illustrated in Fig. 3, corresponds with that described except that it has cast to the underside of its hub 4 a depending rocker arm 25 16 provided with intermediate lugs 17 and a bottom opening 18. The connecting bar (not shown) is adapted to be connected at 18 to the rocker arm and where it is desired to fasten this bar between a pair of rocker 30 arms, two rocker arm segments will be used and their lugs 17 will space their lower ends so that the rocker bar can be inserted between them and bolted thereto. These rocker arm segments can be inserted at any desired 35 point or points along the grate bar to bring same into alinement with the furnace door and thereby to avoid having to drill the boiler front to insert the grate operating mechanism. In assembling the segments on 40 the tubular support 1 they are slipped on an end thereof and the lugs 6 are caused to interfit in the V-shaped grooves 7, so that when the sleeves 2 and 3 are screwed on the tubing 1 and jam the segments together between them, the tongue and groove interlocking parts positively hold the segments in true alinement and prevent relative movement between them. In Fig. 1 I have shown the sleeve 2 screwed up against the lugs 6 45 on the end segment. Such an arrangement is entirely practical though if desired the lugs can be easily removed. Of course a segment can be cast to form an end segment without the lugs 6 but that would require an additional part to be carried and it is my desire to reduce as far as possible the number of parts to be made and to make the assembling of the bar as simple as possible. 50 In operation, the grate bar is rocked back and forth under the fire and, due to the staggered arrangement of the fire heads 8 and 8^a, I am enabled to shift a direct supporting surface from under all parts of the 55 fire and in this manner I can clean the fire

better than where the bar has a continuous straight supporting surface lying in the plane of its rocking movements. The manner in which the supporting webs 13, 14 and 9 are tapered and inclined, prevents any 70 tendency of the clinkers, etc., to catch between the segments as anything that can pass between the fire heads will fall freely between the webs and will not lodge on the rounded top of the hubs. 75

What I claim as new and desire to secure by Letters Patent is:—

1. A rocking grate bar comprising a section of pipe forming a round shaft, a series of fire supporting units, each formed in a 80 single piece and each having a perforated base member mounted on the shaft and having interlocking parts, and sleeves mounted on the ends of the shaft and relatively adjustable thereon for clamping the said units 85 rigidly in position thereon, said sleeves being adapted to reinforce the ends of the tubular shaft and serve as removable trunnions for the grate bar, substantially as described. 90

2. A rocking grate bar comprising in combination a tubular support having its cylindrical ends threaded, a series of grate bar segments having hubs bored to fit on said tubular support, means on the segments to interlock them against relative movement 95 and sleeves screwed on the ends of the tubular support and adapted to clamp the segments in interlocked position and hold them rigidly in position on the shaft, said sleeves being adapted to serve as removable trunnions 100 for the grate bar, substantially as described. 100

3. A grate bar comprising a series of units, each unit comprising a continuous fire head formed by two staggered fire sections 105 disposed on opposite sides of a vertical central axial plane through the grate bar, the fire head sections on the same side of said plane being spaced equi-distantly, and the head sections on one side of said plane being 110 set opposite to, and at their inner ends substantially corresponding in width with, the spaces between the head sections on the other side of said plane. 110

4. In a grate bar, a series of units each 115 formed by a single piece and each having a continuous fuel head formed by two similar half sections which are disposed on opposite sides of the bar, and the inner ends of which meet in offset relationship at the center of 120 the head. 120

5. In a rocking grate bar, a series of units each formed in a single piece and each having a convex fuel head formed by two similar half sections which meet in offset relationship above the center of the bar, said sections having their top faces struck from the same center, and web means to support said faces substantially above the axis of the bar. 125

6. A grate bar segment comprising a body 130

portion, a fire head formed of offset half sections which join at the vertical center of the head, and spaced supports for connecting said fire head to the body portion comprising 5 end webs which are relatively staggered and an intermediate support disposed diagonally of the segment, substantially as described.

7. A grate bar segment comprising a hub, 10 a fire head formed of offset half sections which meet at the vertical center of the head, and webs for connecting said fire head to the hub, said webs comprising end supporting webs which are relatively staggered, and 15 center webs which are oppositely inclined and tapered to bring the base of one adjacent to one side face of the hub and the base of the other adjacent to the other side face of the hub, there being a ventilating 20 space between said webs, substantially as described.

8. A grate bar segment comprising a hub, a fire head formed of staggered sections leading from its axial center outwardly, and 25 four webs for supporting said fire heads, which webs taper downwardly in thickness and are thinner than the top surface of the heads, the end webs being staggered to correspond with the staggering of the fire head 30 sections and the center webs being also staggered at their bases and oppositely inclined both transversely and axially of the segment.

9. A grate bar segment comprising a hub, 35 two integral offset fire heads which extend in opposite directions from the vertical axial center of the segment, a central web 9 for supporting said fire heads at their meeting inner ends, and end webs 13 and 14 for supporting the outer ends of the fire heads, said webs being downwardly tapered, there being 40 ventilating openings in the web 9 and between that web and the end webs, the webs

under one fire head being reversely inclined and staggered relatively to the webs under 45 the other fire head for the free access of air laterally to said openings, substantially as described.

10. In a rocking grate bar, a plurality of units each formed in a single piece and each 50 having a fuel supporting head and a spacing member, said head comprising half sections which are relatively staggered, the inner end of each terminating over the center of the grate bar, and a central web support for the 55 sections having inclined faces extending downwardly and in opposite directions from said inner ends of the sections.

11. A grate bar segment forming part of the sectional bar, said section comprising a 60 base member which is rounded over head, and a fire head comprising two half sections which are offset and meet over the center of said base member, and a web support for 65 said fire head sections, which web extends diagonally across the base member, substantially as described.

12. A grate bar segment forming part of the sectional bar, said section comprising a base member which is rounded over head, 70 and a fire head comprising two half sections which are offset and meet over the center of said base member, and a web support for 75 said fire head sections, which web extends diagonally across the base member and comprises two reversely inclined faces which rise in opposite directions from the base of the web and meet the inner offset ends of the head sections, substantially as described.

In testimony whereof I affix my signature 80 in presence of two witnesses.
